[57] **CLAIM**

The ornamental design for a pair of jaws for folding pliers, as shown and described.

DESCRIPTION

FIG. 1 is an isometric view from the upper left rear of a pair of jaws for folding pliers showing my new design, wherein the broken line depiction of a pair of handles is included for illustrative purposes and forms no part of the claimed design;

FIG. 2 is a top plan view of the pair of jaws for folding pliers shown in FIG. 1;

FIG. 3 is a left side elevational view thereof;

FIG. 4 is a front, or jaw tip, end elevational view thereof;

FIG. 5 is a rear end elevational view thereof;

FIG. 6 is a bottom plan view thereof; and,

FIG. 7 is a right side elevational view.
